CLAIM

An ornamental design for a code reader, as shown and described.

DESCRIPTION

FIG. 1 is a front isometric view of a code reader showing the new design;

FIG. 2 is a front side elevation view thereof;

FIG. 3 is a right side elevation view thereof;

FIG. 4 is a left side elevation view thereof;

FIG. 5 is a bottom plan view thereof;

FIG. 6 is a top plan view thereof; and,

FIG. 7 is a rear side elevation view thereof.

The broken lines in the figures are for illustrative purposes only and form no part of the claimed design.
